[57] CLAIM

The ornamental design for a cable tie, as shown and described.

DESCRIPTION

FIG. 1 is a fragmentary perspective view of the head of the cable tie of FIGS. 3-7;

FIG. 2 is a fragmentary perspective view of the head of the cable tie of FIGS. 3-7;

FIG. 3 is a reduced top view of the cable tie, shown broken away to indicate indeterminate length;

FIG. 4 is a left side view of FIG. 3, the right side being a mirror image thereof;

FIG. 5 is a bottom view of FIG. 3;

FIG. 6 is a reduced end view as seen from the bottom of FIG. 3;

FIG. 7 is a reduced end view as seen from the top of FIG. 3;

FIG. 8 is a fragmentary perspective view of the head of a second embodiment of the cable tie shown in FIGS. 10-13;

FIG. 9 is a fragmentary perspective view of the head of the cable tie of FIGS. 10-13;

FIG. 10 is a reduced top view of the cable tie, shown broken away to indicate indeterminate length;

FIG. 11 is a left side view of FIG. 10, the right side being a mirror image thereof;

FIG. 12 is a bottom view of FIG. 10;

FIG. 13 is a reduced end view as seen from the bottom of FIG. 10; and,

FIG. 14 is a reduced end view as seen from the top of FIG. 10.
